UNITED STATES PATENT OFFICE.

WILBER E. HUNTER, OF MORGANTOWN, WEST VIRGINIA.

DESIGN FOR A TUMBLER, GOBLET, JUG, OR SIMILAR ARTICLE.

45,756.

Specification for Design.

Patented May 12, 1914.

Application filed February 26, 1914. Serial No. 821,312. Term of patent 7 years.

To all whom it may concern:

Be it known that I, WILBER E. HUNTER, a citizen of the United States, residing at Morgantown, in the county of Monongalia and State of West Virginia, have invented a new, original and ornamental Design for a Tumbler, Goblet, Jug, or Similar Article, of which the following is a specification, reference being had to the accompanying drawing, forming a part thereof.

The figure illustrates the design used on a tumbler, goblet, jug or similar article of glassware showing my new design.

I claim—

The ornamental design for a tumbler, goblet, jug or similar article.

WILBER E. HUNTER.
